UNITED STATES PATENT OFFICE

95,126

DESIGN FOR A TEXTILE FABRIC

Curt Erwin Forstmann, Montclair, N. J.

Application January 5, 1935, Serial No. 54,740

Term of patent 14 years

To all whom it may concern:

Be it known that I, Curt Erwin Forstmann, a citizen of the United States, residing at Montclair, in the county of Essex and State of New Jersey, have invented a new, original, and ornamental Design for a Textile Fabric, of which the following is a specification, reference being had to the accompanying drawing, forming part thereof.

In the drawing, the sole figure of which is a plan view of a piece of the textile fabric embodying the design of the present invention, the cloth depicted is of a single color.

The design includes parallel series of spaced

raised bars, the bars of adjacent series being in staggered relation. The bars have a somewhat reticulated appearance. Inclined lines or ridges intersect the spaces between the series of bars, said lines or ridges being substantially less prominent than the bars and being oppositely inclined in adjacent spaces forming sketchily defined quadrilateral figures with the bars at the apices of the angles.

I claim:

The ornamental design for a textile fabric, as shown and described.

CURT ERWIN FORSTMANN.
